CLAIM

I claim the ornamental design for a box, as shown and described.

DESCRIPTION

FIG. 1 is a perspective view of a box, according to the present invention;

FIG. 2 is a left side elevational view thereof;

FIG. 3 is a right side elevational view thereof;

FIG. 4 is a bottom plan view thereof;

FIG. 5 is a top plan view thereof;

FIG. 6 is a rear elevational view thereof; and,

FIG. 7 is a front elevational view thereof.

The dashed lines in the drawings represent perforations which form part of the claimed design.
